Attorney,

UNITED STATES PATENT OFFICE.

JOSEPH IACONO, OF NEW BRUNSWICK, NEW JERSEY.

SPARK-PLUG.

1,306,817.

Specification of Letters Patent. Patented June 17, 1919.

Application filed November 27, 1918. Serial No. 264,288.

To all whom it may concern:

Be it known that I, JOSEPH IACONO, a subject of the King of Italy, (who has declared his intention of becoming a citizen of the United States,) residing at New Brunswick, county of Middlesex, and State of New Jersey, have invented a certain new and useful Spark-Plug, of which the following is a specification.

10 This invention is a spark plug for internal combustion engines, the object in view being to eliminate to a marked degree the deposit of carbon upon the terminals of the electrically operated gas firing elements of the ignition system.

According to my invention, the plug is provided with a longitudinal stem or rod which constitutes one terminal, the other terminal being in the form of a multi-bladed 20 rotary element mounted in such relation to the stem or rod as to produce a spark gap. Said rotary element or terminal is embodied, preferably, in the form of a propeller wheel the blades of which are spirals adapted to 25 be acted upon by the rotative movement at relatively high speed to the rotary element as a unit, whereby any lodgment of lubricating oil, or other liquid or semi liquid matter, upon the rotary element will be 30 thrown off by centrifugal force and thus the deposit and accumulation of carbon upon the plug terminals will be eliminated automatically so that the waste products will be carried out with the exhaust gases and further, the deposit of carbon within the engine 35 cylinder will be reduced to a material extent.

In my device, the propeller wheel terminal is mounted on the plug for rotation 40 on an axis extending at a right angle to the terminal producing rod or stem, and thus the propeller wheel terminal is positioned for the peripheral edges of its blades to be presented in operative relation to the extremity of the stem or rod, thus resulting in a spark gap the length of which is variable 45 owing to the fixed position of the stem or rod and to the rotary motion of the propeller wheel terminal with respect to said 50 rod, as a result of which the arc or spark is drawn out in the normal operation of the plug and a hot spark is produced which insures high combustion, efficiency and economy.

55 Further, it is preferred to incase the propeller wheel terminal within the plug with

a view to excluding to a material extent the lodgment of oil thereon. Accordingly, the inner end of the plug is closed except for the provision of a transverse slot, within 60 which slot is positioned the rotary terminal, so that the sides and edge portions thereof are housed within the surfaces of the plug, although the margins of the slot are open for the free flow or circulation of gases 65 through the slot in order that the spark may explode the charge and the suction of the gases will so act upon the rotary terminal as to impart rapid rotation thereto.

In the drawings,

Figure 1 is a side elevation of a spark plug provided with my new rotary terminal.

Fig. 2 is an end view looking at the inner part of the plug.

Fig. 3 is a view of the plug showing the 75 latter in section on the line 3—3 of Fig. 1 for the better illustration of the rotary terminal.

The body A of the spark plug is polygonal for a part of its length and threaded 80 exteriorly at a in order that it may be screwed into the socket usually provided in the cylinder. Said plug carries a stem or rod B extending longitudinally within an insulation C of any suitable character, the 85 outer end of said rod being provided with a male thread for reception of a nut b usually provided for the attachment of an electrical conductor. At its inner end, the body of the plug is extended or prolonged at d 90 for a suitable distance beyond the threaded part a, said extended part d being made solid except for the provision of a transverse slot D therein, said slot extending across the plug and being open on the opposite faces thereof.

The inner end portion c of the rod or stem extends into the slot D, see Fig. 3, and said end portion c constitutes one of the terminals of the electric circuit by which the 100 spark is produced.

The salient feature of my invention is a rotary terminal E positioned in coöperative relation to the terminal c and carried by the plug for rotation on an axis which is at a 105 right angle to the length of the stem or rod C, as a result of which the rotary terminal is positioned for its peripheral edge to lie opposite to the terminal c and thus produce a spark gap across which the current will leap 110 to produce the required spark. Said rotary terminal E is embodied, preferably, as a

multi-bladed wheel, the blades *e* of which are spirally formed to the end that the flow of gases within the engine cylinder acts upon the blades so as to impart rotative movement 5 to the wheel. As shown, the rotary terminal is formed in a single piece, stamped and struck up from sheet metal, and provided with four blades; but it is apparent that the number of blades and the form thereof are 10 not material and, further, that the rotary terminal may be composed of material other than sheet metal and be manufactured by processes other than by stamping the same.

The rotary terminal is positioned within 15 the slot *D* of the plug and it is mounted therein by a pin or arbor *F*, the latter being fixedly secured in the solid end portion *d* of the plug and said arbor having good electrical contact with the rotary terminal *E* and 20 the plug *A*.

It will be noted that the side and edge portions of the rotary terminal *E* are within the slotted part of the plug, so that the rotary terminal is incased, for all practical purposes, by the slotted part *d* of the plug, thus 25 minimizing the lodgment of oil upon the terminal *E*, but at the same time the gases within the cylinder are free to flow through the space afforded by the slot. The gases 30 are thus ignited by the spark at the plug, and the movement of the gases imparts rotative movement to the rotary terminal *E*, which rotation of part *E* relative to terminal *C* produces a long hot spark for the ignition 35 of the gases.

It is thought the operation and advantages of the invention will be apparent from the foregoing description.

In my spark plug, as a matter of practical 40 construction, it is preferred to so position the rotary terminal in such relation to the fixed terminal that a spark gap of approximately .025 to .030 inch is produced between the peripheral edge of the blades 45 comprising said rotary terminal and the face or edge of the fixed terminal, but it is of course apparent that the width of the spark gap may be changed.

Should the rotary terminal cease to turn 50 on its axis due to the flow of the engine gases as intended by this invention, which cessa-

tion in the rotation may arise for unforeseen conditions, it is to be understood that the spark plug will continue to function and to operate so as to meet the requirements, 55 for the reason that in such event the plug will still act to furnish a spark in the same manner as the ordinary plug with two fixed terminals.

Having thus fully described the invention, 60 what I claim as new and desire to secure by Letters Patent is:

1. A spark plug provided with a terminal, and a rotatable terminal carried by the plug for rotation on an axis extending across the 65 axis of the first terminal, said rotatable terminal being provided with a plurality of blades separated one from the other by intervening spaces and positioned for the peripheral edges of said blades to lie opposite to the first terminal and produces therewith a succession of spark gaps upon the rotation of said terminal.

2. A spark plug provided with a terminal, and a multi-blade terminal carried by said 75 plug and mounted for rotation on an axis extending at an angle to the axis of the plug, said multi-blade terminal being positioned for the peripheral portion of its blades to be spaced relatively to the first terminal and to 80 form a spark gap therewith.

3. A spark plug provided with a terminal, and a rotatable terminal substantially incased by the plug and mounted therein for rotation on an axis extending at an angle to 85 the axis of the plug, said rotatable terminal being positioned for the peripheral portion thereof to produce a spark gap relatively to the first terminal.

4. A spark plug provided at its inner portion with a slot which opens through the respective faces of the plug, a fixed terminal, a rotatable terminal incased within the slot and positioned for the peripheral portions of its blades to produce a spark gap with the 95 fixed terminal, and an arbor in electrical contact with the plug and the rotatable terminal.

In testimony whereof I have hereunto 100 subscribed my name this 22 day of November, 1918.

JOSEPH IACONO.
